UNITED STATES PATENT OFFICE.

BARTHOLOMEW KLOHS, OF CANTON, OHIO.

KEY-CHANGEABLE LOCK.

1,125,343.

Specification of Letters Patent.

Patented Jan. 19, 1915.

Application filed October 28, 1911. Serial No. 657,381.

To all whom it may concern:

Be it known that I, BARTHOLOMEW KLOHS, a citizen of the United States, residing at Canton, in the county of Stark and State of Ohio, have invented a new and useful Key-Changeable Lock, of which the following is a specification.

This invention relates to improvements in locks provided with tumblers adapted to be set up in various combinations, it being possible to change the combination to respond to a new key without the necessity of taking the lock apart, the tumblers being set up to the new combination by the new key itself. The invention is especially applicable to and frequently finds expression in the locks on safety deposit boxes in banks and the like where a large number of such boxes are in use by various depositors and where it is frequently desirable to change the combination of a lock to respond to a new key when the box is rented by a new depositor. Where such locks are used on safety deposit boxes and the like it is frequently desirable to so construct the lock as to require the use, not only of the depositor's key, but also of a custodian's pass key adapted to set up a pass tumbler in the lock not affected by the depositor's key. In the present instance I have shown and shall describe a lock embodying a pass tumbler adapted to respond to a pass key of the character mentioned.

In the use of locks of the kind to which my invention relates, when a depositor desires to unlock his deposit box he is first identified by the custodian of the pass key and such custodian then goes to the appropriate box, inserts his pass key into the lock and sets up the pass tumbler only, the depositor's tumblers being unaffected thereby. The depositor then inserts his own key into the lock and unlocks it by actuating the depositor's tumblers therewith, he being able to do so only after the pass tumbler has thus been set up. When the depositor again turns the key to lock the lock not only the depositor's tumblers but the pass tumbler is thrown down, and in order to again unlock the lock both the pass key and the depositor's key must be used. In some instances it will be understood that the pass key is used, by mistake, to set up the pass tumbler in the wrong lock, the mistake becoming apparent only when the depositor's key fails to operate the tumblers, whereupon the mistake is discovered. In such instance it is desirable that the custodian be

enabled to throw down the pass tumbler thus set up by mistake so that that particular lock cannot be opened by the person holding the depositor's key therefore without being first identified as the proper owner thereof. Provision for this is made in the present invention, as will hereinafter appear.

The objects of the invention are to generally improve key-changeable locks, to simplify construction and reduce the number of parts, to provide a stronger, better and more accurate lock less liable to get out of order and convenient and satisfactory in operation.

It is also an important object of the invention to do away with small parts, especially small moving parts, and to construct the tumblers along substantial lines adapted for proper mechanical operation.

These objects, together with other objects which will be apparent to those skilled in the art, may be attained by the construction illustrated in the accompanying drawings, although the invention may be embodied in other forms, the construction illustrated being chosen by way of example.

In the drawings Figure 1 is a front perspective view of a lock embodying my invention in locked position. Fig. 2 is a front interior view of the lock, the front plate being removed, showing the parts in locked position. Fig. 3 is a similar interior view showing the parts in unlocked position. Fig. 4 is a similar interior view of the lock, the depositor's tumblers and fences being removed and disclosing the pass tumbler and fence in locked position. Fig. 5 is a similar interior view showing the parts in unlocked position. Fig. 6 is a similar interior view of the lock, all of the tumblers and fences being removed and disclosing the bolt plate and rack plate in locked position. Fig. 7 is a similar interior view of the lock showing the parts in the unlocked, unset or neutral position ready to be set up to any desired combination. Fig. 8 is a perspective view of one of the depositor's tumblers. Fig. 9 is a perspective view of one of the depositor's fences. Fig. 10 is a perspective view of the pass tumbler. Fig. 11 is a perspective view of the stationary fence. Fig. 12 is a perspective view of the bolt plate and integral bolt. Fig. 13 is a perspective view of the rack plate with the rack-post attached. Fig. 14 is a perspective view of the bolt actuating key post. Fig. 15 is a sec-

tional view through the rack plate releasing mechanism. Fig. 16 is a perspective view of the rack plate releasing button. Fig. 17 is a plan view of the pass or setting-up key. Fig. 18 is a plan view of a depositor's key. Fig. 19 is a plan view of the unset setting key. Fig. 20 is a back perspective view of the lock.

Throughout the several views similar reference numerals indicate similar parts.

Special attention is now directed to Figs. 1 and 6. The casing of the lock is preferably made of metal and comprises the back plate 1, upper side 2, lower side 3, forward end 4, and rear end 5, all of said parts being formed integrally. The forward end 4 is provided with the bolt aperture 6 through which the bolt 7 of the lock extends. The front plate 8 is removably connected to the lock casing after the various parts have been arranged on the interior thereof, said front plate being connected to the casing by means of the screws 9 which enter screw threaded apertures 10 in bosses formed integrally with the casing. The front plate is provided with the key post collar 11 adapted to extend through the door on which the lock is arranged, the lock being intended to be fastened on the inner side of the door, as is common in lock construction of the sort herein concerned. To facilitate the fastening of the lock to the door the attaching-screw apertures 12 are arranged in the back plate 1 and corresponding notches 13 are arranged in the front plate 8 to permit attaching screws to pass completely through the lock and be connected to the door upon which the lock is arranged. Firmly connected at their bases to the back plate 1 are the vertically spaced fence holding pins 14 and 15 which extend perpendicularly with reference to the back plate 1 and are of the same height as the sides 2 and 3, the front plate 8 being provided with apertures to receive the upper ends of the pins as shown in Fig. 1.

Attention is now especially directed to Figs. 6, 12 and 13. Immediately inside the back plate 1 are arranged the bolt plate 16 and the rack plate 17. The rack plate is clearly illustrated in Figs. 6 and 13 and it will be noted that it comprises a main body portion provided with a horizontal slot 18 adapted to accommodate the fence holding pin 15 as shown in Fig. 6, the slot 18 permitting the rack plate to slide horizontally within the casing. Also formed integrally with the main body of the rack plate is the lower horizontal sliding arm 19 adapted for sliding contact with the lower side 3 and having a sufficiently long horizontal bearing thereon to accurately guide the rack plate in its horizontal sliding movements. In addition to these features the rack plate 65 is provided with an upper bolt plate retain-

ing lug 20 extending upwardly from the bolt plate engaging head 21. At the rear end of the rack plate the portion 22 is provided with a curved releasing-button engaging edge 23, the purpose of which will hereinafter more fully appear. Intermediate the portion 22 and the head 21, from the main body of the rack plate arises perpendicularly the rack-post 24 having upper and lower horizontal parallel sides 25 and 26 respectively. The rack-post is also provided with the forwardly projecting rack teeth 27, said teeth being formed accurately and being vertically disposed with reference to the plane of the plate 17. Said teeth are preferably formed of small cross-section to permit a large variety of delicate adjustments for various combinations as will hereinafter more fully appear. It is immaterial how the rack-post is connected to the plate 17 but it is preferable to provide the plate 17 with a fixedly connected pin 28 and to provide the rack-post with a vertical aperture adapted to receive the pin, the post being prevented from rotation on said pin as will hereinafter appear.

The bolt plate 16, as has been hereinbefore stated, is arranged immediately inside of the back plate 1. The upper horizontal edge 29 of the bolt plate is adapted for sliding contact with the upper side 2 as illustrated in Fig. 6, while the lower horizontal edge 30 is adapted for horizontal sliding engagement with the upper edge of the sliding arm 19. At the rear end of the bolt plate the integral extended portion 31 having the dependent lug 32 is provided, the lower horizontal edge of the portion 31 being adapted for sliding engagement with the upper edge of the lug 20 of the rack plate and the lug 32 being adapted to engage the lug 20 to limit the movement of the bolt plate away from the rack plate, as is clearly illustrated in Fig. 6. The rear vertical edge 33 on the bolt plate is adapted to engage the forward edge of the head 21 on the rack plate when the rack plate and bolt plate are moved. It will be thus understood that when the rack plate and bolt plate are arranged within the casing as shown in Fig. 6 the said plates will be limited in their sliding movement toward and away from each other and will assist in maintaining each other in proper position within the casing. At the forward end of the bolt plate the integral bolt 7 is provided which extends through the bolt aperture 6 in the forward end 4 of the casing, as hereinbefore described. At the upper portion of the plate 16 the shoulder 34 is provided which shoulder is adapted to engage the lug 35 formed integrally with the casing to limit the forward movement of the bolt plate as illustrated in Fig. 6. In the body of the plate 16 the cam opening 130

36 is provided, said opening being so formed as to provide the upper forward and rear shoulders 37 and 38 respectively from which lead the curved forward and rear cam edges 39 and 40, said shoulders and cam edges being adapted to be engaged by the cam 41 of the key post 42. When the cam 41 and plate 16 are in the positions illustrated in Fig. 6 the curved cam face of the cam 41 is in engagement with the forward cam edge 39, thus holding the plate 16 in its most forward position, the bolt 7 being extended through the opening 6. If the key post 42 is rotated to throw the cam 41 upwardly and backwardly the curved cam face of the cam 41 will move along the edge 39 and past the shoulder 37, thence freely moving backwardly into positive engagement with the shoulder 38. A further backward movement of the cam 41 will carry the bolt plate 16 backwardly, to unlocked position as shown in Fig. 3. If the cam is then further turned backwardly the curved cam face thereof will come into engagement with the rear cam edge 40 so that when the key post 42 is in the position illustrated in Fig. 7 the bolt will be held in fully retracted position as firmly as it is held in extended position in Fig. 6.

30 The rack plate releasing button, as illustrated in Fig. 16, comprises the stud 43, the integral circular flange 44, and the integral stem 45. At the rear end of the back plate 1 said plate is provided with the stud receiving aperture 46, said plate being preferably provided with a boss around the said aperture, as shown in the drawings, and being adapted to slidably receive the stud 43, the flange 44 being arranged immediately on the inside of the plate 1 as shown in Fig. 15. The front plate 8 on its inner side and opposite the aperture 46 is provided with a spring holding lug 47 which extends inwardly toward the stem 45. The coiled compression spring 48 extends from the flange 44 to the plate 8 and is arranged upon the stem 45 and lug 47 in order to keep it in proper operative position. The spring is adapted to normally hold the flange 44 against the inner side of the plate 1, as shown in full lines in Fig. 15, but the button may be pushed inwardly against the tension of the spring 48 until the stem 45 comes into engagement with the lug 47, the stud 43 being slidably moved within the aperture 46, and the flange 44 being moved inwardly away from the inner side of the plate 1 into the position shown in dotted lines in Fig. 15. When the rack plate 17 is 60 in its extreme forward position, being limited in forward movement by the pin 15 in the slot 18, the flange 44, lying against the inner side of the plate 1, will be immediately to the rear of the portion 22 of the rack plate, the edge 23 being in engagement with the peripheral edge of the flange 44. When the rack plate releasing button is pushed inwardly, however, as just above described, the flange 44 will be moved out of engagement with the rack plate, thus releasing the 70 rack plate and permitting it to move backwardly, the portion 22 thereof sliding under the flange 44, and between said flange and the back plate 1, the backward movement of the rack plate being limited by the slot 18 75 and the pin 15 hereinbefore described. This position is illustrated in Fig. 7, where it will be noted that the rack post 24 has moved backwardly with the plate 17 to which it is connected, as hereinbefore described.

At this point attention should be called to the fact that so long as the flange 44 is in engagement with the plate 17, thus holding the plate 17 in its forward position, the plate 16 cannot be moved backwardly farther than unlocked position shown in Figs. 3 and 5, the cam 41 on the key post 42 being turned backwardly but slightly farther than the vertical position, being 80 prevented from turning farther backwardly by the engagement of the cam 41 with the rear shoulder 38 of the plate 16. When, however, the rack plate releasing button is pushed inwardly and the rack plate 17 85 thereby released, further backward rotation of the post 42 is possible, the cam 41 carrying backward both the plate 16 and the plate 17 into the position illustrated in Fig. 7, where it will be noted the cam 41 is 90 disposed directly backward, the post 42 having made a one-half revolution from the position illustrated in Fig. 6. The collar 11 on the plate 8 is provided with the forward key-way 49 and the rear key-way 50 only, 95 said key-ways constituting slots of the usual well known construction and being disposed diametrically opposite each other. The post 42 is provided with the external head 51 adapted to rotatably fit within the collar 11, said head 51, post 42 and cam 41 being provided with the key receiving slot 52. From an inspection of Fig. 1 it will be evident that a key may be inserted or withdrawn from the lock only when the post 42 100 is turned with the cam 41 in its extreme forward or extreme backward position, it being impossible to remove the key from the lock when the spindle is but partially rotated backwardly, as for instance in the position 105 shown in Figs. 3 and 5.

In a lock of my invented construction all of the depositor's tumblers are constructed in exactly the same way, all of said depositor's tumblers being of the same shape, size 110 and proportions. This is also true of all of the depositor's fences used in the lock. If a pass tumbler is used, however, said tumbler is of somewhat different construction from the depositor's tumblers and a 115

65

stationary fence, differing from the depositor's fences, should also be used in connection with such pass tumbler.

As illustrated in the drawings, and especially in Fig. 8, each depositor's tumbler comprises two members, a tumbler member proper and a spring member. The tumbler member proper is preferably stamped from sheet material in the form illustrated in Fig. 8, there being a forward head portion 53 provided with a vertically disposed slot 54, a rearwardly extending stem portion 55 and a rear head portion 56 extending downwardly from the stem 55 and having a rearwardly open gate 57 and below said gate a vertically disposed slot 58 similar to the slot 54 and extending parallel therewith. The spring 59 is fastened at its forward end to the forward portion of the head 53 by the insertion of the forward end of said spring in a slot 60 in accordance with well known practice, the spring 59 when free from restraint, extending rearwardly and upwardly from the head 53 at an angle to the stem portion 55.

As especially illustrated in Fig. 9 each depositor's fence is preferably stamped from sheet material of the same thickness as the material from which the depositor's tumblers are stamped, each fence comprising a main vertically disposed body portion 61 provided near its top and bottom ends with the vertically disposed slots 62 and 63 respectively. Formed integrally with the body portion 61 are the rearwardly projecting rack teeth 64 adapted to mesh with the rack teeth 27 of the post 24 but said teeth 64 being preferably considerably greater in number than the number of teeth on said rack post so as to afford opportunity of considerable vertical adjustment as between each fence and the rack post 24. Also formed integrally with the body portion 61 is the forwardly extending stub 65.

It will be understood that in the assembling of the lock one depositor's fence should be used for each depositor's tumbler and the stub 65 of each fence is adapted to enter the gate 57 in the corresponding depositor's tumbler when said tumbler and fence are in appropriate relative vertical adjustment.

The pass tumbler is most fully illustrated in Fig. 10 and comprises two members, the pass tumbler member proper and the spring member. The pass tumbler member proper is preferably stamped from sheet material and comprises a forwardly projecting head 66 having an aperture 67 therein, said aperture being substantially divided into forward and rear portions by the depending tip 67, thus producing a heart shaped aperture. The pass tumbler also has the main body portion 68 having the pin-passing apertures 69 and 70 and also the rearwardly open gate

71. In the midst of the main body portion 68 is arranged the pass key aperture 72 concerning which it should be noted that at the forward edge of said aperture is provided a key-entering notch 73 from which leads the 70 curved upwardly and rearwardly inclined cam edge 74 terminating in the upper notch 75 to the rear of which is the integral depending lug 76. The purpose of these details of construction will hereinafter more 75 fully appear. The spring 77 is connected to the forward end of the pass tumbler by the insertion of the forward end of said spring in the slot 78, in accordance with usual practice, and extends, when unstrained, upwardly 80 and backwardly at an angle to the substantially horizontal upper edge of the tumbler.

As illustrated in Fig. 11, the stationary fence is preferably stamped from sheet material of the same thickness as that from which the pass tumbler is stamped, the stationary fence comprising the main, vertically disposed body portion 79 having arranged therein the vertically spaced apertures 80 90 adapted to receive the fence holding pins 14 and 15 fixedly connected to the plate 1 as hereinbefore described. Formed integrally with the main body of the stationary fence are the rearwardly projecting, spaced, rack-post holding portions 81 having oppositely disposed parallel edges adapted to slidably engage the upper and lower sides 25 and 26 of the rack-post, so that while the rack post may move with the fence plate 17 backwardly and forwardly between the portions 81 said portions will prevent said post from turning and will guide its movements in a true and exact manner. Formed integrally with the body portion 79 is the forwardly 105 projecting stub 82.

It will be understood that if one of the pass tumblers such as described is used in the assembling of the lock, that one of the master fences such as described should also be used, the stub 82 being adapted to be slidably received into the gate 71 when the pass tumbler is in proper vertical adjustment.

Fixedly connected to the bolt plate 16 and extending vertically therefrom at the forward end thereof is the pass tumbler pin 83. Somewhat above and to the rear of the pin 83 the forward depositor's tumbler pin 84 is arranged, while considerably to the rear and on the lower portion of the plate 16 is the rear depositor's tumbler pin 85. The pins 84 and 85 are fixedly connected to the plate 16 and extend vertically therefrom substantially to the front plate 8.

In assembling the lock the bolt plate 16 125 and rack plate 17 are arranged immediately inside the back plate 1 as hereinbefore described and as clearly shown in Fig. 6. The depositor's tumblers and fences and the pass tumbler and stationary fence may then 130

be arranged in the following manner:—One depositor's tumbler is arranged immediately on top of the plate 16, the slots 54 and 58 of said tumbler receiving the pins 84 and 85 and the spring 59 being brought under the spring tensioning pin 86 fixedly connected to the plate 16, so as to throw the said spring under tension to normally hold the rear end of the tumbler with its head 56 in the lowermost position. One of the depositor's fences is then arranged with the fence holding pins 14 and 15 extending through the slots 62 and 63 and the rack teeth 64 rearwardly disposed so as to mesh with the teeth 27 when the post 24 is moved into the forward position. This depositor's tumbler and its corresponding depositor's fence in the same plane will hereinafter be termed the "depositor's first set." 10

On top of the "depositor's first set" is arranged the "pass set" comprising the pass tumbler and the stationary fence. The pass tumbler is arranged with the pin 83 extending through the aperture 67, while 15 the pin-passing apertures 69 and 70 freely receive the pins 84 and 85. It will be noted that the bolt 7 is provided with a rearwardly open recess 87 and the head 66 of the pass tumbler partially enters said recess 20 when said pass tumbler is in its most forward position with relation to the plate 16, the pin 83 in such case being located to the rear of the tip 67^a as illustrated in Figs. 4 and 7. The spring 77 is arranged under the 25 pin 86 to normally hold the rear end of the pass tumbler in its lowermost position and the stationary fence is arranged with the pins 14 and 15 extending through the apertures 80 thus preventing vertical and horizontal relative movement as between the stationary fence and the back plate 1. The rack post 24 is mounted upon the pin 28 between the portions 81 as hereinbefore described and is thus prevented from vertical movement but may be moved horizontally frontwardly and rearwardly with the 30 plate 17.

On top of the pass set is arranged the "depositor's second set" consisting of one depositor's tumbler and one depositor's fence of exactly the same construction as the tumbler and fence comprising the "depositor's first set," the slots 54 and 58 receiving the pins 84 and 85 and the slots 62 and 63 receiving the pins 14 and 15 as hereinabove set forth. On top of this "depositor's second set" may be similarly arranged any practical number of similar depositor's sets in accordance with the degree of complexity desired. 35

Attention is now directed to the keys adapted to be used in the lock and illustrated in Figs. 17, 18 and 19. It will be noted that said keys are of the flat variety 40 and are provided with the integral shoul-

ders 88 adapted by engagement with the inner side of the plate 8, to prevent the keys from being withdrawn from the lock except when said keys are turned to either of the key-ways 49 or 50, which key-ways 70 slidably receive said shoulder. The keys are also provided with the integral lug 89 adapted to enter the slot 52 of the cam 41 to give a firm bearing with said cam for the turning thereof by the key. Intermediate 75 the shoulders 88 and the lugs 89 the depositor's keys are provided with various bittings such as illustrated in Fig. 8, while the pass or setting-up key is provided with the bitting shown in Fig. 17 and the unsetting key 80 is provided with the bitting shown in Fig. 19. It will be noted that the pass or setting-up key is provided with the one tooth 90 only and the unsetting key is provided with the one tooth 90^a only located in the same 85 relative position as the tooth 90 but longer than said tooth 90. The teeth 90 and 90^a are adapted to engage the pass tumbler only, as will hereinafter be more fully described. Each depositor's key is fully cut away at 90 the place, 91, corresponding to the teeth 90 and 90^a, so that none of the depositor's keys will affect the pass tumbler. Each depositor's key is, however, provided with a plurality of other teeth 92 adapted to actuate 95 the depositor's tumblers, the teeth of the various depositor's keys equaling in number the depositor's tumblers and all of said teeth varying in length by units equal to the pitch of the teeth of the fences and rack 100 post 24.

Let it be supposed that the lock is assembled and in the position illustrated in Fig. 7, which is the unlocked, unset or neutral position. The teeth of the rack-post being out 105 of engagement with the teeth of the fences and all of the depositor's tumblers and fences being in the lowermost position. If it be desired to set up the depositor's tumblers to a combination corresponding to any 110 desired depositor's key, the depositor's key in question is inserted into the lock when the parts are as shown in Fig. 7 and the key turned in contra-clockwise direction. The various teeth of the depositor's key will 115 raise the individual depositor's tumblers to various corresponding heights so that when the bitting of the key stands vertically the various depositor's fences will have been raised to various heights by their respective 120 tumblers, each "depositor's set" assuming a distinct, individual position, depending upon the particular bitting of the key. The length of the different teeth of the bitting being varied by a unit of measure equal to the 125 pitch of the teeth on the fences and rack post, the rack teeth 64 on the various fences will be arranged in alinement so as to mesh with the rack teeth 27 of the post 24. By further contra-clockwise rotation of the key 130

the cam 41 will be brought into engagement with the forward shoulder 37 of the bolt plate 16 and the bolt will be thrown forward into extended, locked position such as shown in Fig. 6. As the bolt plate 16 moves forward the dependent lug 32, engaging the lug 20 of the rack plate 17 will move said rack plate, with the rack post 24 thereto attached forwardly into the position illustrated in Fig. 2, or Fig. 6. As said rack post moves forwardly the rack teeth 27 thereof move into mesh with the rack teeth 64 of the depositor's fences, thus holding them in the fixed relative vertical adjustment, and when the plate 17 has moved sufficiently forwardly, the spring 48 will move the rack plate releasing button outwardly, throwing the flange 44 into position behind the portion 22 of the rack plate, thus retaining the rack plate in its forward position and preventing any undesired releasing of the rack post from the fences. In this locked position, as illustrated in Fig. 6, the rack plate will be held in its forward position firmly engaging the various fences by the rack teeth 27 and will be prevented from any backward movement not only by the flange 44, but also by the engagement of the lug 20 with the dependent lug 32, all parts, when in the position illustrated in Fig. 6 being thus most thoroughly and firmly locked. As the bolt plate 16 with the various tumblers thereto connected moves forwardly the gates of the various tumblers leave the 30 stubs 65 and the tumblers thereupon drop into their lowermost positions, as shown in Fig. 2, with the rear edges of their head portions 56 engaging the ends of the stubs 65. At this time the key will have been revolved contra-clockwise one-half revolution, the bolt 7 will be in the extended, locked position and the key may be removed, the shoulder 88 passing out through the forward key-way 49.

45 By the operation just described it will be noted that the various fences have been vertically adjusted with reference to each other to correspond to the bitting of the particular depositor's key desired and that said fences will be retained in said positions, the combination being thus set up so as to respond to the particular depositor's key and to no other. At the time when the various tumblers left their engagement with the stubs 50 of the fences, the pass tumbler did the same so that in the locked position the pass tumbler is in its lowermost position with its rear end edge bearing against the end of the stub of the pass fence. The depositor's keys all being cut away at 91 cannot affect the pass tumbler and therefore when it is desired to unlock the lock the pass or setting-up key illustrated in Fig. 17 must first be used. In using said pass or setting-up key it is inserted in the slot 52 when the

parts are in the position shown in Figs. 2 or 4 and said key is then turned in clockwise direction, the tooth 90 riding up the cam edge 74, engaging the lug 76, and lifting the pass tumbler upwardly and backwardly so that the stub 82 of the pass fence is entered partly into the gate 71 of the pass tumbler, and the pass tumbler is bodily moved backwardly so that the pin 83 is brought into that portion of the aperture 67 in front of the tip 67^a. In this position the pass tumbler is said to be "set up". When the pass tumbler has thus been set up the setting-up key may be turned contra-clockwise and removed from the lock when the cam 41 has been turned into the forward position shown in Figs. 2 or 4 without throwing down the pass tumbler. The depositor's key to which the lock combination has been set may then be inserted and turned in clockwise direction, whereupon the lock will respond to said key, the teeth of said key setting up the various depositor's tumblers to appropriate height so that the stubs of the depositor's fences may enter the gates of the 90 depositor's tumblers and the bolt may be retracted to the extent shown in Fig. 3, the normally unlocked position of the bolt. At this point the rear vertical edge 33 of the bolt plate 16 will come into engagement with the front edge of the head 21 of the rack plate 17 and normally prevent further retraction of the bolt and further rotation of the key. If, now, it be desired to throw the parts into the neutral position shown in Fig. 7 so as to set up the lock for a new combination the stub 43 should be pressed inwardly, thus removing the flange 44 from behind the portion 22 of the rack plate and permitting further clockwise rotation of the key to the extreme backward position illustrated in Fig. 7, whereupon the parts will be in neutral position and the depositor's key may be removed.

It will be understood that at times the pass or setting-up key may, by accident be used upon the wrong lock and in order to accomplish the throwing down of the pass tumbler the unset setting key illustrated in Fig. 19 is employed. This key is provided with a slightly longer tooth 90^a than the tooth 90 of the pass or setting-up key. Should it be desired to throw down the pass tumbler after it has been set up as hereinbefore described by the pass or setting up key the key illustrated in Fig. 19 may be inserted when the cam 41 is in its most forward position and the key turned in clockwise direction, the tooth 90^a riding up the cam edge 74 and drops into the upper notch 75, when by a contra-clockwise rotation the tooth 90^a, pressing forwardly upon the side of the notch 75 will move the master tumbler forwardly so as to throw the pin 83 back of the tip 67^a, thus removing 130

the stub 82 from the gate 71 of the pass tumbler and permitting the pass tumbler to drop into its lowermost position illustrated clearly in Fig. 4, whereupon it will 5 be again necessary to use the setting up key previous to the appropriate depositor's key in order to unlock the lock.

By reason of the fact that both the tumblers and fences move in true vertical lines 10 at right-angles to the horizontal lines in which the bolt plate moves, extreme accuracy is attained, making it possible to form the stub of each fence so as to comparatively closely fit the gate of its corresponding 15 tumbler. A pivoted tumbler in case of wear either on the part of the tumbler or key, greatly exaggerates the misadjustment because of the fact that the gated end of such tumbler moves through a greater arc than the 20 portion of the key which actuates it, whereas in applicant's construction the entire tumbler moves vertically to exactly the same extent as the portion of the key which actuates it and any wear on the part of the 25 key or tumbler is not at all exaggerated in any portion of the tumbler.

In conclusion attention should be called to the fact that by different location of the pass tumbler and pass fence with respect to 30 the depositor's sets, the number of possible combinations may be greatly multiplied. While in the lock herein shown and described the said pass tumbler and fence are located between the depositor's first and second sets, it will be obvious that the same 35 may be arranged between any other two of the depositor's sets. In this way different safety deposit institutions located in the same city may be supplied with locks requiring 40 different pass keys so that it will be impossible for the keys belonging to the locks in one institution to be used on the locks on any other institution. This is all accomplished by the mere difference in 45 arrangement of the sets in the lock and requires no difference in construction of parts.

I claim:

1. In a key changeable lock, in combination 50 with varying keys, a lock casing, a bolt mounted therein and adapted for movement to assume an extended, locked position, a partially retracted, unlocked position and a fully retracted, neutral position, a plurality 55 of tumblers connected to and movable with said bolt, operable by said keys and adapted for individual movement with relation to said bolt in lines transverse to the line of movement of said bolt, the individual 60 movement of said tumblers being variable in accordance with the variations in said keys, a plurality of fences connected to said casing, adapted for co-action with said

tumblers and adapted for individual movement parallel to the individual movements 65 of said tumblers, means for holding said fences in adjusted position and for simultaneously preventing complete retraction of said bolt, said means when in position to hold said tumblers in fixed position being 70 unaffected by movement of said bolt from the locked to the unlocked position or vice versa, said means being adapted to be released independently of said keys to release said fences and permit complete retraction 75 of said bolt.

2. In a key changeable lock, a casing, a bolt and integral bolt plate mounted in said casing and adapted for forward and backward sliding movement and adapted to assume an extended, locked position, a partially retracted unlocked position and a fully retracted neutral position, a rack plate mounted in said casing and adapted for forward and backward sliding movement therein, 80 said rack plate provided with a rack, tumblers mounted upon said bolt plate and adapted to move forward and backward therewith and also adapted for individual movement transverse to the line of movement of said bolt plate, fences mounted in said casing and adapted for individual movement transverse to the line of movement of said rack plate, means preventing forward or backward 95 movement of said fences within said casing, said tumblers adapted for coaction with said fences, said rack on said rack plate adapted to engage and hold said fences in fixed adjustment when said rack plate is in 100 its forward position, but adapted to free said fences to permit individually independent adjustment thereof when said rack plate is moved to its rear position, said bolt plate adapted to move said rack plate 105 to its forward position when said bolt plate is moved to throw said bolt to the locked position, said bolt plate adapted to move to the unlocked position without moving said rack plate, said rack plate adapted to 110 normally prevent movement of said bolt plate to the neutral position, stop means adapted to normally hold said rack plate in its forward position but adapted to be actuated to permit backward movement of 115 said rack plate, and said bolt plate adapted to move said rack plate to its rear position when said stop means is so actuated.

In testimony that I claim the above, I have hereunto subscribed my name in the 120 presence of two witnesses.

BARTHOLOMEW KLOHS.
